TURNTABLE FOR PHONOGRAPHS AND SOUND RECORDERS

Vernon L. Roberts, Chicago, Ill., assignor of one-half to Richard H. Wann, Detroit, Mich.

Application November 27, 1941, Serial No. 420,725

11 Claims. (Cl. 274—39)

My invention relates to turntables for phonographs and sound recorders, and has to do more particularly with a turntable which is especially designed for home machines which are adapted for making and playing sound records.

In the manufacture of commercial sound discs, it is customary to equip the disc with an eccentric control groove communicating with the terminal portion of the spiral sound groove, this eccentric groove functioning to impart an in-and-out movement to the reproducing stylus and tone arm. Said movement actuates a stop mechanism, record changing mechanism, or the like.

In the making of home records, it has heretofore not been considered feasible to apply to the record such an eccentric groove and this has resulted in considerable inconvenience to the user because of the necessity of manual control following the playing of each home recording.

In my copending application, Serial No. 387,-800, filed April 10, 1941, now Patent No. 2,309,276, granted Jan. 26, 1943, I have suggested a means of providing an eccentric groove to a record by making certain changes in the standard form of record.

An object of the present invention is to provide means for accomplishing the same result by modifying the standard form of turntable, without the necessity of changing the construction of the standard record. According to my invention, special means is provided on a turntable whereby a record may be rotated alternatively either on its true center or on an axis offset from the center of the disc, resulting in an eccentric groove.

Another object is to provide such an arrangement which will be simple in construction, inexpensive to fabricate and, in general, entirely satisfactory for the purposes desired.

Referring now to the drawing forming a part of this specification and illustrating certain preferred embodiments of my invention—

Fig. 1 is a top plan view of a turntable constituting one means of practicing my invention;

Fig. 2 is a diametrical sectional view taken substantially along the line 2—2 of Fig. 1;

Fig. 3 is a plan view showing another embodiment of my invention;

Fig. 4 is an elevational view taken from a point substantially along the line 4—4 of Fig. 3;

Fig. 5 is a plan view of still another embodiment of my invention; and

Fig. 6 is a perspective view of an element of the embodiment shown in Fig. 5.

Referring first to the form shown in Figs. 1 and 2, the numeral 10 represents generally a turntable mounted on a support 12, the latter being in turn rotatably connected to motor drive mechanism (not shown). The turntable 10 is provided with a spring-pressed locking pin 15 which is adapted to seat in a recess in a record at a point near the

center thereof to prevent slippage between the record and turntable, and the turntable is also provided with a center threaded hole 16 receiving a locking spindle 18 for securing the record through its center aperture in axial alignment with the turntable.

According to my invention, another threaded aperture 20 is provided in the turntable at the same distance from the locking pin 15 as the aperture 16. This aperture 20 is preferably disposed as close to the center aperture 16 as possible, in order that a control groove of smallest diameter may be provided and thus permit production of a record of maximum length.

Use of the turntable just described will be readily apparent. The blank record is first secured to the turntable with its center hole in registry with the turntable center hole 16, the clamping element 18 being threaded into the hole 16 and the locking pin 15 in registry with the recess formed for the purpose in most standard records. The record is made by traversing the cutting stylus in a spiral path from a point near the periphery of the record to some point between the periphery and the center, in accordance with standard practice. After the sound groove has been completed, the record is removed from its original position to a position with its center hole in registry with the off-center threaded hole 20. This operation, of course, may be done without removing the record from the turntable, since it may be slid thereon while being retained with its locking recess in engagement with the locking pin 15. The record is then again secured by the clamping element 18 with its center hole in registry with the off center hole 20 of the turntable. The recording stylus is then replaced in the sound groove at or adjacent the inner terminus thereof and the turntable is again set in motion. Obviously this will result in the formation of an eccentric groove, since the record will be rotated on an eccentric axis. Hence, when the record is played, this eccentric groove will function in a manner similar to commercially made records to actuate an automatic stop or other mechanism.

In the embodiment shown in Figs. 3 and 4, a similar result is obtained by providing an arm 25, this arm being pivotally secured as by a stud 27, which may, if desired, extend through the turntable and function as a record locking pin similarly to the pin 15 in Figs. 1 and 2. The arm 25 carries a stud 30 adjacent its inner extremity, this stud extending through a slot 32 passing through the center of the turntable. This slot is preferably an arc having as a radius its distance from pin 27. The arm 25 extends beyond the periphery of the turntable to provide a handle portion, as seen best in Fig. 3, and the marginal flange 33 of the turntable may be provided with a pair of spaced slots 34, 34' snugly receiv-

ing the arm 25, an elongated slot 35 connecting the slots 34 and 34'. The arm 25 by its own resilience or otherwise may be firmly retained alternatively in one of the slots 34, 34'.

It will be seen that when the arm is fixed in the slot 34', the pin 30 is centrally disposed with reference to the turntable while, when the arm is moved into the slot 34, the pin is off center, where it will function in the formation of an eccentric groove in a record.

In the embodiment shown in Figs. 5 and 6, the turntable 10 is provided with a tapered socket 40, which extends from the center of the turntable to a point therebeyond. In this socket is seated a similarly tapered plug 42 which carries, preferably integrally therewith, a stud 45. It will be seen that by reversing the plug 42 in the socket 40 the stud 45 may be positioned either centrally of the record or off center, so that it may be used in the manner described above either for the formation of a spiral groove or an eccentric groove. The socket 40 preferably extends through an arc drawn with a radius having as a center the locking pin 15'.

Various modifications may suggest themselves to those skilled in the art without departing from the spirit of my invention and, hence, I do not wish to be restricted to the specific form shown or uses mentioned, except to the extent indicated in the appended claims.

I claim:

1. A turntable for supporting a record disc which has a central aperture, and a stud upstanding from said turntable and engageable in said aperture of the disc, means enabling said stud to be adjusted from a position at the center of the turntable to a position eccentric thereto, and means positively holding the stud at either position against movement transversely of its axis.

2. A turntable for supporting a record disc which has a central aperture, a driving stud eccentrically disposed in the turntable, and a second stud upstanding from the turntable and engageable in said aperture of the disc, and means enabling said stud to be adjusted from a position at the center of the turntable to a position eccentric thereto, said second stud being disposed at the same distance from said driving stud in both positions.

3. A turntable for supporting a record disc which has a central aperture, a driving stud eccentrically disposed in the turntable, a lever fulcrumed on the under side of the table at the axis of said driving stud, the table having an opening in its central portion and a second stud carried by said lever and upstanding through said opening for engagement in the aperture of the disc, said opening in the table being dimensioned to accommodate the stud at the center of the table and also at a position eccentric thereto and the lever being movable about its axis to shift said stud from one position to the other.

4. A turntable for supporting a record disc which has a central aperture, a driving stud eccentrically disposed in the turntable, a lever fulcrumed on the under side of the table at the axis of said driving stud, the table having an opening in its central portion and a second stud carried by said lever and upstanding through said opening for engagement in the aperture of the disc, said opening in the table being dimensioned to

accommodate the stud at the center of the table and also at a position eccentric thereto and the lever being movable about its axis to shift said stud from one position to the other, together with means which locks the lever when the stud is adjusted at either of said positions.

5. A turntable for supporting a record disc which has a central aperture, said table having a recess formed at the center of the table and extending outwardly for a limited distance, a stud dimensioned to fit the aperture of the disc, and means supporting said stud in the recess of the table and upstanding from the latter, said supporting means being adjustable to position said stud either adjacent one end of the recess and at the center of the table or adjacent the other end of the recess and in eccentric relation to the table.

6. A turntable for supporting a record disc which has a central aperture, a driving stud eccentrically disposed in the turntable, said table having a recess formed at the center of the table and extending outwardly for a limited distance, a second stud dimensioned to fit the aperture of the disc, means supporting said second stud in the recess of the table and upstanding from the latter, said supporting means being adjustable to position said second stud either adjacent one end of the recess and at the center of the table or adjacent the other end of the recess and in eccentric relation to the table, said second stud being disposed at the same distance from the driving stud in both positions.

7. A turntable for supporting a record disc which has a central aperture, a threaded stud dimensioned to fit the aperture of the disc, the table having a threaded opening at its center to receive the stud and a second threaded opening for said stud at an eccentric position.

8. A turntable for supporting a record disc which has a central aperture, the table having a recess, a block fitted in said recess with a stud upstanding from the block dimensioned to engage the aperture of the disc, said block being adjustable in the recess with the stud disposed either at the center of the table or in eccentric relation thereto.

9. A turntable for supporting a record disc which has a central aperture, the table having a pair of recesses, one at the center of the table and one in eccentric relation thereto, and a stud removably and selectively engageable in either recess and dimensioned to project above the surface of the table when so engaged and to fit the aperture of the disc.

10. A turntable for supporting a sound record, a record positioning element carried by said turntable for positioning a record in definite relations thereto, said turntable having means to support and hold said element in alternative positions, one of said positions being co-axial with said turntable and the other position being eccentric to said turntable.

11. A turntable to support a record disc, and a stud in upstanding relation to said turntable to project upwardly into an aperture at the center of the record disc, said turntable having space co-axial therewith and space eccentric thereto, for accommodating said stud selectively in co-axial and eccentric relation to said turntable.
